UNITED STATES PATENT OFFICE

AUGIE L. HANSEN, OF CHICAGO, ILLINOIS, ASSIGNOR TO JUSTRITE MANUFACTURING COMPANY, OF CHICAGO, ILLINOIS, A CORPORATION OF ILLINOIS.

LAMP.

1,109,221.

Specification of Letters Patent. Patented Sept. 1, 1914.

Application filed December 11, 1913. Serial No. 805,960.

To all whom it may concern:

Be it known that I, AUGIE L. HANSEN, a citizen of the United States, and a resident of Chicago, in the county of Cook and State of Illinois, have invented certain new and useful Improvements in Lamps, of which the following is a specification.

My invention relates to lamps, particularly to a portable lamp adapted for connection with a portable fluid supply reservoir.

Among the important objects of the invention are to provide a simple, light and inexpensive lamp of comparatively great power and efficiency which can be readily carried, as for example on a miner's cap, and which is also useful elsewhere; to provide improved burner structure and simplified and improved means for adjusting such structure with reference to the reflector and which can be readily removed from the lamp for inspection or for lighting purposes independently of the reflector; and to provide other desirable features of construction and arrangement.

In the accompanying drawings which clearly illustrate the various features Figure 1 is a side elevational view; Fig. 2 is a top view, Fig. 3 is a sectional view taken on line 3—3, Fig. 2, Fig. 4 is a front view with the lens removed, Fig. 5 is a front view of the supporting plate with the adjustable burner structure thereon, and Fig. 6 is a side view of the burner structure.

In the mechanism shown a supporting plate 10 mounts the lamp shell 11 which is of parabolic or other desired cross-section and preferably of some light metal as aluminum; this shell being secured to the plate by an axially extending rivet 12 and by rivets 13 passing through the upper end 14 of the supporting plate, and also by a rivet 15 passing through spacer block 16. The inner end of rivet 12 may also clamp to the back of the shell a reflector 17 as shown. The lower part of the shell has the entrance opening 18 for a burner 19, and at the upper part of the shell is the outlet or chimney opening 20. Above this outlet 20 is a hood or guard frame 21 having its front end riveted to the shell as indicated at 22, the rear wall 21^a of the frame being inserted between the shell and the upper end 14 of the supporting plate 10 to be held in place by the rivets 13. The side walls 21^b and 21^c have the outlet openings 23 and the top

wall of the frame has outlet 24 which is spanned by the cap plate 25 riveted to the frame and spaced therefrom as clearly indicated.

The burner 19 is mounted on the horizontal base plate 26 having side tongues 27 and the intermediate tongue 28 extending upwardly from the rear end thereof. Extending from the opposite side edge of the supporting plate 10 are guide brackets 29 forming guide-ways for the side tongues 27. The intermediate tongue is preferably sprung with reference to the outer tongues (Fig. 6) in order that when the side tongues are slid into the brackets they will be caused to engage frictionally therein so that this burner supporting structure will be locked in any adjusted position. The burner 19 has a suitable tip 30 and by sliding the burner supporting structure on the supporting plate 10 the flame may be adjusted relative to the shell and reflector or the burner structure may be entirely withdrawn for inspection or for use of the flame independent of the reflector and shell. A suitable nozzle 31 extends from the burner to receive a hose which connects with a fluid supply tank or receptacle. The horizontal base 26 of the burner structure will readily hold the lamp in upright position on a table or other support. A hook 32 may also be provided for hanging the lamp from a support, the hook being shown riveted to the rear wall 21^a of the hood frame 21. To adapt the lamp for support from a cap, as for example a miner's cap, the plate 10 is preferably provided with laterally extending arms 33 bent at their ends to form clips 34 for engaging about the edges of a suitable supporting plate secured to the cap. When the lamp is thus applied the hook 32 will be designed to engage in a suitable opening at the top of the supporting plate on the cap, the lamp being then securely held in place. The supporting plate 10 may be at any desired angle with the axis of the reflector shell in order that when the lamp is applied to a cap with the plate 10 substantially in vertical position the rays of the lamp will be deflected either upwardly or downwardly. Where the lamp is used on a cap or is to be carried about, the fluid tank can be readily supported on the back of the wearer or from his belt.

The front of the reflector shell 11 may remain open, or a lens 35 may be inserted

and held in place by a spring ring 36 in the usual manner. Vent holes 37 may also be provided in the shell adjacent the outlet.

The lamp described can be constructed to be exceedingly light and of pleasing appearance. The construction and arrangement which enables the burner to be readily adjusted or to be entirely removed for inspection is very desirable. The sliding friction connection between the burner structure and the supporting plate is very simple yet very efficient.

I do not desire to be limited to the precise construction and arrangement shown and described as modifications are no doubt possible which would still come within the scope of the invention, and I claim the following:

1. In a lamp of the class described, the combination of a supporting structure having guide-ways, a reflector secured to said structure, a burner, and a supporting frame for said burner having frictional slidable engagement in said guide-ways whereby said burner may be adjusted with reference to said reflector.

2. In a lamp, the combination of a supporting plate having guiding brackets, a burner structure having tongues extending therefrom and adapted for slidable engagement in said brackets, and a spring tongue for co-operating with said supporting plate to cause said other tongues to engage frictionally with said brackets.

3. In a lamp, the combination of a supporting plate having guiding brackets, a burner structure slidable on said plate in said brackets, and a spring tongue on said structure for causing frictional engagement of said structure with said brackets.

4. In a lamp, the combination of a supporting frame, a shell secured to said frame and having an opening at its under side, said supporting frame having guide-ways, a burner extending through said opening into said shell, and a supporting structure for said burner having adjustable slidable engagement in said guide-ways whereby said burner may be readily adjusted with reference to said shell.

5. In a lamp, the combination of a supporting frame, a reflector shell secured to said frame and having an opening in its

lower side, guide brackets on said frame, an L-shaped supporting frame, and a burner secured to the horizontal wall of said L-shaped supporting frame and extending through said opening into the shell, the upwardly extending wall of said L-shaped frame having slideable adjustable engagement in said guide brackets whereby the burner frame may be readily adjusted with reference to the shell or readily entirely disconnected from said supporting frame.

6. In a lamp, the combination of a supporting frame, a reflector shell secured to said frame and having an upper opening and a lower opening, a burner structure adjustable on said frame and having its burner end extending through said lower opening into the shell, a top frame secured to the shell over said upper opening and having an upper outlet, and a cap secured over said outlet.

7. In a lamp, the combination of a supporting plate having guide-ways, an L-shaped frame having its upwardly extending wall adjustably slideable in said guide-ways, a burner extending upwardly from the horizontal wall of said frame, and a fluid inlet nozzle extending from said burner, said horizontal wall forming a supporting base for the structure.

8. In a lamp, the combination of a supporting plate having lateral guide-ways, a reflector shell secured to said plate and having a lower opening, an L-shaped frame, a burner extending upwardly from the horizontal wall of said frame and through said opening into the shell, a fluid inlet nozzle extending from said burner, the upwardly extending wall of said frame having adjustable slideable engagement in said guide-ways whereby said L-shaped frame may be readily moved to adjust the burner with reference to the shell or to be entirely removed from the shell, the horizontal wall of said L-frame forming a supporting base for the lamp structure.

In witness whereof, I hereunto set my hand this 10th day of December, A. D., 1913.

AUGIE L. HANSEN.
